UNITED STATES PATENT OFFICE.

JOHN R. LOMAS, OF NEW HAVEN, CONNECTICUT, ASSIGNOR TO B. SHONINGER, OF SAME PLACE.

DESIGN FOR AN ORGAN-CASE.

Specification forming part of Design No. 5,317, dated October 17, 1871.

To all whom it may concern:

Be it known that I, JOHN R. LOMAS, of New Haven, in the county of New Haven and State of Connecticut, have invented a new and original Design for an Organ-Case, of which the following is a description:

The photograph represents a front elevation of my new organ-case.

This invention relates to several new forms and ornamental combinations of organ-cases. The invention consists chiefly in a new configuration of the upper part of the organ-case, showing the book-rack *a*, set back of two side posts, *j j*, said rack being put in stationary. The faces of the posts are nicely paneled, as shown. The invention consists also in a new configuration of ornamental book-rack *a*, which is made of scroll-work tastefully designed, as shown. The invention also consists in a new form of lamp-brackets, *b b*, whose shanks are in form of arabesques, while their cups are calyx-shaped, as shown. The invention also consists in the clock *c* and head piece *d*, combined to form a new design for the top of an organ. The invention also consists in the design of a wreath, *e*, and stand *f* to said head piece, as an imaginary casing and sup-

port for the clock. The invention also consists in the new configuration of the said head piece *d*, whose outline is of bold and artistic design. The invention consists, furthermore, in a new design of lid, *i*, for the key-board, said lid being of the same cross-section as the end molding *G*, as can be seen (with the aid of a magnifying glass) at the right-hand end of the photographic illustration. The invention also consists in a new form of end and corner molding of the key-board.

I claim as my invention—

1. The design for the upper part of an organ-case, with the stationary book-rack set between and back of two posts *j*, as shown.
2. The design for a book-rack, *a*, as shown.
3. The design for lamp-brackets *b*, as shown.
4. The design for an organ-case, having a clock, *c*, as shown.
5. The design for the clock-case *e f*, as shown.
6. The design for the head piece *d*, as shown.
7. The design for the lid *i*, as shown.
8. The design for the end and corner molding *g*, as shown.
